DESIGN FOR A HAT

Isaac Slott, New York, N. Y.

Application January 26, 1940, Serial No. 89,743

Term of patent 3½ years

To all whom it may concern:

Be it known that I, Isaac Slott, a citizen of the United States of America, residing in New York city, in the Borough of Manhattan, county and State of New York, have invented a new, original, and ornamental Design for a Hat, of which the following is a specification, reference being had to the accompanying drawing, forming part thereof, wherein,

The characteristic feature of my design resides in the superimposed pocket member on the front of the hat as shown.

I claim:

The ornamental design for a hat, substantially as shown and described.

ISAAC SLOTT.
